UNITED STATES PATENT OFFICE.

THEODORE C. PARSONS, OF OAK PARK, ILLINOIS.

BLANK FOR INSURANCE ACCOUNTING.

1,393,823.

Specification of Letters Patent. Patented Oct. 18, 1921.

Application filed August 23, 1920. Serial No. 405,309.

To all whom it may concern:

Be it known that I, THEODORE C. PARSONS, a citizen of the United States, and a resident of Oak Park, in the county of Cook and State of Illinois, have invented a new and useful Improvement in Blanks for Insurance Accounting; and I do hereby declare that the following is a full, clear, and exact description of the same, reference being had 10 to the accompanying drawings, and to the numerals of reference marked thereon, which form a part of this specification.

This invention relates to a system of accounting, wherein a central concern deals 15 with numerous agencies and in which accounts between said central concern and the several agencies are balanced at regular periods.

It is an object of this invention to provide 20 a convenient means whereby the central concern may quickly obtain a balance in the accounts between it and the agencies.

It is also an object of this invention to provide a means whereby the central agency 25 may render to the local agents a statement of account on which the local agent may enter certain additional figures.

A further object of this invention is to provide a set of blanks whereby the business 30 between the central concern and the local agents may be conveniently conducted, which blanks are adapted to the use of book-keeping machines in the office of the central concern.

35 It is a further object of this invention to so prepare the blanks that they may be readily used with carbon paper to avoid the necessity of frequent copying of data onto different records.

40 Other and further important objects of the invention will be apparent from the specification and drawings.

A preferred form of the invention is illustrated in the drawings and is hereinafter 45 more fully described.

On the drawings:

Figures 1 and 1^a together form a view of an agent's accounts current sheet.

Fig. 2 is a view of one sheet of the agent's 50 register adapted to coöperate with the agent's accounts current sheet, illustrated in Figs. 1 and 1^a.

Figs. 3 and 3^a together form a view of the agent's credit memorandum blank, adapted

to coöperate with the agent's accounts current sheet, illustrated in Figs. 1 and 1^a. 55

Fig. 4 is an illustration of the agent's accounts current sheet, superposed upon the agent's register sheet as the two would be placed in making certain entries. 60

Fig. 5 is a view of the agent's credit memorandum blank superposed upon the agent's accounts current sheet as the two would be placed in making certain entries. 65

As shown on the drawings:

In Fig. 1 the agent's accounts current sheet is shown as having a heading 1, with a blank 2 for the month, and a blank 3 for the year. The heading also has at 4 the name of the central concern and at 5 the name of the insurance company with whose policies the records on said blank are concerned. At 6 is a heading with a blank for the location of the agency whose data are recorded on said sheet. The agent's accounts current sheet is divided into two portions by a central line 7. The left hand portion of this sheet has a heading 8 to indicate the nature of the risks underwritten by the policies recorded on this portion of the sheet. 70 It is intended that other sheets, headed with the name of the same company and agency, shall be used for other classes of insurance. 75

The left hand column 9 of this sheet has the heading 10, indicating that the numbers 80 of the policies are to be found in this column. If the business is properly conducted the spaces opposite these numbers will be filled in consecutive order, consequently any empty spaces will indicate that a policy 85 form has not been accounted for by the agent and will call attention to the irregularity. The next column 11 is for the entry of the month as is indicated by the heading 12. The next column 13 is for the entry 90 of the amount of policy as is indicated by the heading 14. The heading 15 applies to all of the columns from 16 to 19 inclusive, and indicates that they contain premiums. Each of these columns except 19 is headed 95 100 as indicated at 20 by figures indicating a rate per cent. These figures show the rate at which the agent is entitled to charge commission upon the premium in the column beneath each figure. The last column 19 has at 105 its head no indication of a rate per cent. but only a blank space. This column is for the premiums on which the agent is entitled

to an unusual or extra commission and not all of the premiums included in this column are to have the commission computed at the same rate.

5 A space is provided at the bottom of each column for the total of the entries therein as is indicated by the designation 21, Fig. 1^a. If the entries for the month occupy more than one page this total can be carried forward 10 and this is indicated by the designation 22. The opposite face of the sheet can be used for this purpose. If the figures recorded upon the sheet do not suffice to fill a whole column, there is no objection to entering 15 the totals at a higher point as indicated at 23, Fig. 1.

On the right hand side of the sheet is the heading "Recapitulation" at 24. On this portion of the sheet there is a column 25 headed as is shown at 26 by indicia intended to stand for rate of per cent. of commission and the various lines in this column contain designations 27 for the corresponding lines in the adjacent columns, showing 25 that these lines receive entries of commission at the several rates of per cent.

To the left of column 25 in a column 28 are entered the totals 23, from the columns 16 to 19 inclusive, as is indicated by the 30 heading "Gross Premiums" at 29. This column also has an insignia 30 to indicate that debtor items are there entered.

To the right of column 25 is a column 31 for the entry of the commissions computed 35 as indicated. The heading 32 shows the nature of the entries and the heading 33 shows that they are credit entries. A space is provided at the foot of column 30 for the entry of the total 34 of the items in this column, 40 and a space is provided at the foot of column 31 for the total 35 of the entries in this column. The nature of these sums is indicated by the legends 36 and 37 respectively.

45 At the bottom of the right hand side of the agent's accounts current sheet, is a portion 38 headed by a title 39 which indicates that this portion is to be used for the record of policies canceled. This portion is 50 divided in a way analogous to the left hand portion of the sheet. The divisions have corresponding designations. The divisions and the designations are indicated by reference numerals 40 to 54 respectively, which 55 have a similar meaning to the corresponding reference numerals beginning with 9 in the left hand portion of the sheet.

The entries in this portion of the sheet should be made in a distinctive color and the 60 headings and rulings for these columns should be in that color in order that the entries therein may not by any accident be confused with the entries on the left hand portion of the sheet. This is indicated on 65 the drawing by making these items in ob-

lique lettering while other entries are shown in upright lettering.

Immediately below the portion of the recapitulation table, described heretofore, is another portion which is for the summary 70 of the items concerning the policies canceled. This constitutes the middle section of the recapitulation part of the sheet. The lowest section of the recapitulation part of the sheet will be described later, after the blank for 75 the agent's credit memorandum has been described. The column 55 at the left of the central portion of the recapitulation table is for the entry of the total of columns 47 to 50 inclusive, which is indicated by the heading 80 56. This column and its heading does not stand immediately under the column 28 but is placed to the left thereof in order that the entries to be made therein shall not occupy the space between the total of column 85 28 and the total of column 55. The latter total is placed to the right of the bottom of column 55 as indicated at 57. The designation showing the nature of this total and the direction to deduct it from the total above 90 are in the place which the total would ordinarily occupy directly under the column 55, as shown at 58. A rate of per cent. is indicated opposite each line, of 55 as shown by 95 59, to indicate the rate at which the commission on the several premiums should be computed. The commissions thus computed are shown in column 60 under the heading 61 indicating that these are commissions which because the insurance has been canceled 100 must be returned. The column 60 is not under the column 31 but is to the right thereof in order that entries therein may not come between the total of column 31 and the total of column 60. The total of column 60 105 is placed to the left of the foot of this column as shown at 62. The space below column 60 which is ordinarily occupied by the total is used for the designation and directions 63. These directions indicate that this total must 110 be subtracted from the total of column 31. The total 62 being deducted from the total 35, the difference is shown at 65, just as the difference between the total 34 and the total 57 is shown at 64. The spaces for these differences are designated as shown at 67 and 66 respectively, to show the nature of the amounts therein. The amount due the company or due the agent as the case may be is found by subtracting one of these two numbers 64 and 65 from the other and is placed at 70 or at corresponding place to the left of 70 as the case may be. The places for this 115 final result are designated as shown at 68 and 69.

The agent's register sheet, shown in Fig. 2, is headed by the name of the agency and the name of the agent as indicated at 71 and 71^a respectively. The sheet is divided into two parts by the line 72. The left hand part 130

- is designated at 73 to indicate that it is for policies written and the right hand side has the designation 74 showing that it is for policies canceled. The remainder of the 5 designations are like those already described under the corresponding titles upon the agent's accounts current sheet. The left hand portion of the agent's accounts current sheet has rulings which will register with the 10 rulings upon the left hand portion of the agent's register sheet. The vertical rulings upon the right hand side of the agent's accounts current sheet will at the same time register with these rulings upon the right 15 hand half of the agent's register sheet, but the horizontal rulings and the heading upon the two halves of the agent's accounts current sheet will not all register with the corresponding headings and rulings upon the 20 agent's register sheet at the same time. The agent's accounts current sheet must be differently positioned upon the agent's register sheet for entries upon each side of the center vertical line. This is no disadvantage because 25 each accounts current sheet is placed in the bookkeeping machine at the time the information to be entered thereon is obtained from the daily report of the agent and the accounts current sheet as well as the agent's 30 register sheet is returned to its place in a loose leaf binder or other file after each entry. Since it is necessary to reposition the agent's accounts current sheet upon its respective agent's register sheet for each entry, there 35 would be no time saved by having the rulings on the two sides of the vertical central line in register at the same time. As the several headings for columns upon the agent's 40 register sheet are like the corresponding headings upon the agent's accounts current sheet, there is no need for repeating the particular description of them.
- The agent's credit memorandum blank is shown in Figs. 3 and 3^a and is divided vertically into two portions by a line 108 of perforations enabling the two parts to be readily separated. The upper part of the right hand portion has a heading 75 to indicate the location of the agency. Below this is 45 a heading 76 corresponding to the heading 24 upon the agent's accounts current sheet. The space below this heading contains columns and designations like those found on the agent's accounts current sheet indicated by the reference numerals from 25 to 37 and below this there is on the right hand part of the agent's credit memorandum blank a set of spaces, columns and designations like those on the agent's accounts current sheet in the places marked by reference characters 56 to 70. These columns and designations are located in the same relative position and are of the same size as the corresponding columns and designations on the 55 agent's accounts current sheet so that when the two are superposed the upper right hand part of the agent's credit memorandum blank will register with the upper right hand part of the agent's accounts current sheet. 70
- The left hand part of the agent's credit memorandum blank contains at the top a blank for the entry of the month 77. There is also at the top of this sheet a set of directions 78 indicating that the left hand portion of the agent's credit memorandum blank is to be returned to the central concern. The sheet also contains at 79 directions for its use and directions that the statement accompanying the sheet is not to be returned to 80 the central concern but is to be retained by the agent. The tabular portion of the left hand part of the sheet has the heading "Credit Memo." at 80 indicating that it is to be used for a statement of items of the 85 agent's business not included in the statement rendered by the central concern. Below this is a set of columns, the first one 81 having at 82 a heading Policy No., indicating that this column is to be used for the 85 entry of the numbers of policies mentioned in this memorandum. The next two columns 83 and 85 have at 84 and 86 the headings Date and Gross Ret. Prem. and have the combined heading Cancellations or 90 Rebate, at 87. Below the column 85 is a space with the designation at 88 Total Gross Ret. Prem., the headings for these columns and the designations just mentioned are printed in a distinctive color to indicate that they 95 are related to items that will cause the balance due from the agent to the central concern to be smaller than shown by the agent's account current as made out at the central agency. The next two columns are given 100 the common heading 88^a Premiums or Add'l. Prem., indicating that they are for premiums or for additional premiums. The first of these columns indicates the rate per cent. for computing the commission and 110 the next column indicates the premium and they have headings showing their purpose. These headings are shown by numbers 89 and 90. At the foot of column 90 is a space 91 for the total thereof and this is designated by the designation 92. Below this is 115 space 94 to receive the total of the commissions computed by the rates indicated in column 89. This and the fact that it is to be subtracted is indicated by the designation 120 93. The result of this subtraction stands at 95 directly under a space 96 designated to indicate that the entry therein is the balance due the company as per statement attached. This space contains an entry equal to the entry shown at the space 70 on the agent's account current sheet. The designations and rulings indicated by the reference characters from 88 to 95 inclusive are in the same color as the designation of space 96 which is the 125 130

same as the entries on the left hand part of the agent's account current sheet as is indicated by the upright style of the lettering. Directly under the space 88 is a space 97 with the designation 96, showing that it contains the total of the commissions on the returned premiums. The designation also indicates that this is to be subtracted. At the right of the space 97 is a space 98 in which the results of this subtraction is written. This is the first of a list of items to be credited to the agent. The designation of all of this list is printed in the same color as the heading 87.

15 Beneath the designation 96 there is a series of designations 97^a to indicate the nature of each of a list of items. These are for the correction of inaccurate charges concerning the commissions on policies already reported or for other corrections needed to adjust the month's balance. These may be either additive or subtractive. When the latter, they are indicated by encircling the amount as shown at 98^a. At 25 99 there is a space for the entry of the total of all the agent's charges. There is a designation 100 adjacent the same to show its nature and also to indicate that it is to be subtracted from the figure just above at 101. 30 These figures were obtained by adding the figures at 95 to those at 96 as indicated by the directions in the designation 102. At 103 the result of the whole of this computation is indicated and the designation showing that this is the result is found at 104. 35 At 105 there is a space for the date and at 106 a space for the signature of the agent, each of the spaces being suitably designated to indicate its purpose. Below this there is 40 a space 107 for the name and the address of the agent. The space 77 for the month, and the space 107 for the name and address of the agent as indicated by the designation 107^a will register with a space similarly designated, upon the other face of the right hand part of the agent's credit memorandum statement when the sheet is folded. The last named designation does not show in the drawing.

45 50 The system in which these papers are used contemplates the employment of book-keeping machines and of machines operated by punched cards for tabulating the results. At the beginning of the month, the work is begun by filling in the headings at the top of the agent's accounts current sheet and the agent's register sheet. There is a set of these sheets for each agent and, when the central concern is the joint 55 60 activity of several insurance companies, if any agent acts for more than one company, there will be a corresponding number of accounts current sheets and of agent's register sheets, for that agent. The agent's accounts 65 current sheets are filed loosely but the agent's

register sheets are kept in loose leaf binders, one for each company or if the business is large enough a set for each company, a set being one register for each district.

When a report is received from an agent 70 indicating that a policy has been written, the agent's accounts current sheet is taken from the file of the said sheets, and the agent's register sheet is taken from its place in the loose leaf binder and the two sheets 75 are placed in the bookkeeping machine with agent's accounts current sheet superposed upon the agent's register sheet so that the spaces for the entries concerning this insurance shall register as shown in Fig. 4. Carbon paper 150 is placed between these sheets 80 and the entries concerning the policy reported by the agent are made in their proper places. The papers are then returned to their respective places in the file of accounts 85 current and in the agent's register. When another report is received from the same agent this operation is repeated with the same sheets and a separate set of entries is made for each policy reported. When the 90 report shows that a policy has been canceled the agent's accounts current sheet and the agent's register sheet are placed in the bookkeeping machine so that the portion 95 38 of the agent's accounts current sheet shall register with the portion for canceled insurance upon the agent's register sheet, with carbon paper between the sheets. Ordinarily this will require the agent's accounts current sheet to be placed higher 100 upon the agent's register sheet than when recording the writing of insurance.

As the end of the month approaches, the blank for the agent's credit memorandum is prepared by filling in the heading at 75 105 and 77. At the end of the month the totals of columns, 16 to 19 and 44 to 50 are found and entered by carbon paper upon the agent's register sheet at the same time that they are entered upon the agent's accounts current 110 sheet. The agent's accounts current sheet and the agent's credit memorandum blank are then placed in register with carbon paper 151 as shown in Fig. 5 and the recapitulation tables are filled out. The result of this operation (shown at 70) is reproduced as shown at 70^a at the place in register with 70 upon the right hand part of the agent's credit memorandum blank. This sum is copied into the space 96 upon the 120 left hand part of the blank.

The agent's accounts current sheet Figs. 1 and 1^a and the agent's credit memorandum blank Figs. 3 and 3^a are then sent to the agent who keeps the accounts current sheet 125 as directed by the last line of the legend 79 on the agent's credit memorandum blank. The agent then fills out columns 81 and 83 and enters the amounts under headings 86 or 90 according to whether the insurance in 130

question was canceled or written. In the latter case he fills out the entry under heading 89 but in the former case no corresponding entry is provided for as the central concern already knows what rate of commission should be allowed on canceled insurance. The agent then makes the calculations indicated by the legends 92 and 93, and obtains the figures for the space 95. He then by following the directions 102 obtains the sum 101. By adding the column 85 he obtains the footing 88 and from this subtracts the return commissions as indicated by 96. The result 98 is suitably placed to be added with the rest of the items indicated by 97^a. This sum 99, the directions 100 show, must be subtracted to get the corrected balance due the company 103.

The third section of the recapitulation part of the agent's accounts current sheet has a series of designations 109 designating spaces wherein the agent may write a copy of the results of his entries under the designations 97^a on the agent's credit memorandum blank. Spaces 110, 111, and 112 are also provided wherein the results in spaces 95, 101 and 99 on the agent's credit memorandum blank may be recorded and these spaces are designated to show their purpose. By placing the designations 109 so that their entries come under column 25 the spaces 110, 111, and 112 naturally come under the space 70 and render easy the computation of the corrected balance which is entered at 113. The agent can thus enter on the sheet which he is to retain a copy of the results of the data he has sent to the central concern on the agent's credit memorandum blank. The agent then returns the credit memorandum blank to the company and keeps the accounts current sheet for his own file.

The agent reports daily to the central concern the business done that day. Immediately after the records concerning the several policies reported as written or canceled by the agent have been entered by means of the bookkeeping machines, cards are punched to represent the same data. These cards are used with the card sorting and tabulating machine and the balance obtained by means of these tabulating machines must agree with the balance obtained by the bookkeeping machines. When these agent's credit memorandum sheets are returned by them after the end of the month, a similar method to compute the corrected balance is used based upon another set of punched cards, and using the tabulating machines. These cards are punched from the data sent in on the agent's credit memorandum blanks.

This system dispenses with the need of deferring the audit of the agent's account until after the end of the month. Each daily report of the agent's transactions is incorporated into the totals yielded by the bookkeep-

ing and tabulating machines. The check afforded by the fact that these two mechanical results must agree makes certain that the balance rendered by the central concern to the agent (at 70 and 96) is a correct statement of his account as it stands on the books of the central concern. The only matter needing a check therefore is the correction to the balance caused by the agent having on his books items not on the books of the central concern. These are the items which the agent enters on the agent's credit memorandum blank. The audit of these is obtained by the tabulating machines operating on the second set of cards as above explained.

It is evident therefore, that at the end of the month there is very little work left to do, as compared with what remains at that time under former systems, to arrive at a statement of the condition of the central concern's business. Moreover the use of the tabulating machines permits this remaining work to be very quickly done. The present system thus enables a statement of the condition of the business to be obtained nearly thirty days earlier than under former systems.

It is to be understood that wide variations in the details of headings and arrangement of columns may be made without departing from the spirit of this invention, and it is not the intention to limit this patent to such details of headings or arrangements otherwise than is necessary because of the prior art.

I claim as my invention:

1. A sheet having a field designated to receive data concerning insurance written, containing a set of columns each designated by the indication of a rate of per cent., the set as a whole being designated to indicate that the several columns are to receive premiums, a space adjacent each column designated to indicate that it is to receive the total of the entries in that column, a second field containing a column designated to indicate that it is to receive said totals, each line of said column being designated by a rate of per cent. and another column designated to indicate that it is to receive commissions and having its lines designated by the same rates per cent., a space adjacent and in alinement with each of said columns each designated to indicate that it is to receive the total of its column, a third field containing columns and spaces similar to the first field and a fourth field containing columns and spaces similar to the second field, the columns of the fourth field being adjacent to but out of alinement with the total spaces of the second field, being separated by a greater distance than the columns of the second field whereby they are out of alinement with the columns of the second field, spaces adjacent to but out of alinement with the columns of the fourth

field and suitably designated to indicate that they are for the totals of said columns respectively, said total spaces being in alinement with the columns of the second field, whereby 5 the totals of the corresponding columns of the second field and fourth field will be separated by spaces containing no entries.

2. A sheet having two fields each having columns of suitable size to receive data and 10 spaces of suitable location to receive the totals of the data in said columns, said sheet also having a field with two parts, each part containing columns, each column having as many lines as there are columns in one of 15 the first named fields, corresponding lines in the columns in the two parts bearing like designations, each column in each of the first named two fields having a designation like that of the corresponding line in the third 20 field, each part also having for each column a space suitably located to receive the total of said column, the columns in one of said parts being separated more widely than the columns in the other part but the spaces for 25 totals being the same distance apart in each part whereby the totals are conveniently located for computation.

3. A sheet having two fields each having columns of suitable size to receive data and 30 spaces of suitable location to receive the totals of the data in said columns, said sheet also having a field with two parts, each part containing columns, each column having as many lines as there are columns in one of 35 said first named fields, corresponding lines in the columns in the two parts bearing like designations, each column in each of the first named two fields having a designation like that of the corresponding line in the third 40 field, each part also having for each column a space suitably located to receive the total of said column, the columns in one of said parts being separated more widely than the columns in the other part but the spaces for 45 totals being the same distance apart in each part whereby the totals are conveniently located for computation, in combination with a sheet having a tabular field like said third field and another field, spaces in said last 50 named field suitably designated to receive data showing how the result computed from the totals in said third field should be adjusted and suitably designated spaces in said last named field for computing the said 55 adjustment, spaces adjacent said tabular field suitably designated to receive the result of said computation, said first named sheet having a fourth field containing suitably designated spaces for the recording of the items 60 entering into said adjustment.

4. A sheet having a field designated to receive data concerning insurance written, containing a set of columns each designated by the indication of a rate of per cent., the set 65 as a whole being designated to indicate that

the several columns are to receive premiums, a space adjacent each column designated to indicate that it is to receive the total of the entries in that column, a second field containing a column designated to indicate that 70 it is to receive said totals, each line of said column being designated by a rate of per cent. and another column designated to indicate that it is to receive commissions and having its lines designated by the same rates 75 per cent., a space adjacent and in alinement with each of said columns each designated to indicate that it is to receive the total of its column, a third field containing columns and spaces similar to the first field and a 80 fourth field containing columns and spaces similar to the second field, the columns of the fourth field being adjacent to but out of alinement with the total spaces of the second field, being separated by a greater distance than the columns of the second field, whereby they are out of alinement with the columns of the second field, spaces adjacent to but out of alinement with the columns of the fourth field and suitably designated to 85 indicate that they are for the totals of said columns respectively, said total spaces being in alinement with the columns of the second field where the totals of the corresponding 90 columns of the second field and fourth field 95 will be separated by spaces containing no entries, in combination with a second sheet containing columns and spaces like those in the second and fourth fields of the first mentioned sheet, having similar designations 100 and being suitably located to register with the columns and spaces of the second and fourth fields when said sheets are superposed, said second sheet also containing spaces suitably designated and arranged 105 for the computation of a correction of the result computed in said second and fourth fields, there being on said first sheet a fifth field containing suitably designated spaces for the insertion of the data on which such 110 computation is founded and a suitably designated space for the corrected result.

5. A sheet having a field designated to receive data concerning insurance written, containing a set of columns each designated by 115 the indication of a rate of per cent., the set as a whole being designated to indicate that the several columns are to receive premiums, a space adjacent each column designated to indicate that it is to receive the total of the 120 entries in that column, a second field containing a column designated to indicate that it is to receive said totals, each line of said column being designated by a rate of per cent. and another column designated to indicate that it is to receive commissions and having its lines designated by the same rates 125 per cent., a space adjacent and in alinement with each of said columns each designated to indicate that it is to receive the total of its 130

column, a third field containing columns and spaces similar to the first field and a fourth field containing columns and spaces similar to the second field, the columns of the fourth field being adjacent to but out of alinement with the total spaces of the second field, being separated by a greater distance than the columns of the second field, whereby they are out of alinement with the columns of the 5 second field, spaces adjacent to but out of alinement with the columns of the fourth field and suitably designated to indicate that they are for the totals of said columns respectively, said total spaces being in alinement with the columns of the second field 10 whereby the totals of the corresponding columns of the second field and fourth field will be separated by spaces containing no entries, in combination with a second sheet 15 20 containing columns and spaces like those in the second and fourth fields of the first mentioned sheet, having similar designations and being suitably located to register with the columns and spaces of the second and fourth fields when said sheets are superposed, said second sheet also containing spaces suitably designated and arranged for the computation of a correction of the result computed in said second and fourth fields, there being on said first sheet a fifth field containing 25 30 suitably designated spaces for the insertion of the data on which such computation is founded and a suitably designated space for the corrected result, the portion of said second sheet like said second and fourth fields 35 being separated from the portion for computing the correction by a weakened line whereby it may be readily detached therefrom.

In testimony whereof I have hereunto subscribed my name in the presence of two subscribing witnesses.

THEODORE C. PARSONS.
